US0D1031213S

(12) United States Design Patent (10) Patent No.: US D1,031,213 S
(45) Date of Patent: * Jun. 18, 2024

(54) SHOE

(71) Applicant: FUZHOUSHI YONGTAIXIAN
PAMEILA Trading Co., Ltd., Yongtai
County (CN)

(72) Inventor: Rongrong Cai, Xianyou County (CN)

(73) Assignee: FUZHOUSHI YONGTAIXIAN
PAMEILA Trading Co., Ltd., Yongtai
County (CN)

() Term: 15 Years

(21) Appl. No.: 29/919,261

(22) Filed: Dec. 3, 2023

(51) LOC (14) Cl. 02-04
